Heidrich & Lauten
ATTORNEYS

UNITED STATES PATENT OFFICE.

ARTHUR L. OTTO, OF PHILADELPHIA, PENNSYLVANIA, ASSIGNOR TO ORANGE SCREEN COMPANY, OF MAPLEWOOD, NEW JERSEY, A CORPORATION OF NEW JERSEY.

METALLIC SCREEN.

Application filed November 17, 1924. Serial No. 750,488.

My invention relates to a certain new and useful construction in metallic screens for windows, doors and the like, whereby a solid and integral metallic screen frame structure is produced, which will be in the true sense of the word a single unitary structure without any mechanical or visible joints or seams of any kind, being in effect a continuous metallic structure throughout the periphery and the frame and which frame moreover will be provided with suitable screen retaining grooves or recesses or channels, as well as suitable channeled, solid or rounded outer edges, to adapt the same for various uses to which such screens are put, namely to adapt the same to sliding as well as to hinged screens for windows, doors and the like.

With the above ends in view my invention consists of a certain new and novel metallic screen, and the method of making the same, whereby the frame is produced which is much more serviceable, durable and rigid than metallic screen frames produced heretofore, and which in addition to the above advantages are far more attractive in appearance than the screens and screen frames known heretofore, which have been made exclusively of sheet metal.

My invention further consists of a novel method of making metallic screens and screen frames which consists in extruding through the suitable dies a solid metal, screen retaining channel piece, severing said screen retaining channel piece into suitable lengths with mitred ends, welding or fusing such ends together to form suitably sized and shaped integral, unitary and continuous metallic screen frame, having a suitable screen retaining channel along the inner edges of one of its faces. Aluminum or aluminum alloy is preferred for the screen retaining channel pieces, since in addition to lightness they impart other advantages to the screen frame, as will be brought out hereinafter.

My invention further consists of a novel screen frame structure which in addition to being possessed of extreme strength and rigidity, will also be light and which will be provided with novel screen retaining

means within said inner screen retaining channels, for replaceably securing metal screening to the frame.

It has been customary heretofore in making metallic screen frames, to shape the frame members out of strips of bendable sheet metal; bending the sheet metal back upon itself into various complex cross sectional shapes in an effort to obtain a rigid structure. Due to the very nature of the construction, however, no screen frame of any considerable size could be produced sufficiently rigid without the use of some reinforcing means. This was particularly noticeable in the case of the mitred corner joints, which heretofore have been soldered along the thin contacting edges of the sheet metal, and in addition to the soldered joint, have been braced in some manner. This construction, however, gave results not entirely satisfactory, and particularly so in screen frames of large proportions in which case the screen was subject to distortions.

By my present invention moreover, an extruded metallic screen frame may be provided having screen retaining channels in a face thereof, of substantially uniform cross-section and having the walls thereof substantially parallel, and having a substantially parallel walled anchoring member seated in said channels, adapted to secure the edges of a screen fabric therein, without the aid of any positive interlocking means, such as the interlocking of the splines in the inwardly enlarged screen retaining channels employed in the built up sheet metal screen frames of the prior art, used extensively heretofore.

This securing action between the screen cloth, pressed flatly, and relatively lightly, against the inner surface of the channel, with the dislodging force acting at a right angle to the line of extrusion of said frame members and said channel, is due partly to the interengagement obtained between the apparently and relatively smooth extruded surfaces of the channel and anchor member on one hand, and the raised or high intersecting points of the wires of the screen cloth and the series of minute, parallel longitudinal ridges and furrows, the

"grain" of the metal, on the other hand, which are formed in the apparently smooth inner walls of the channel as a result of extrusion, longitudinally of, and parallel to, 5 said channel.

This novel locking action between the relatively smooth walls of the channel and the anchor member and screen cloth, may further be augmented, by extruding the 10 frame members of a relatively malleable and yet rigid and strong metal, such as aluminum or an aluminum alloy; since by such novel means a further locking action is obtained, by the gradual embedding of 15 the raised or high intersecting points of the wires of the screen cloth, in the inner surface of the screen retaining channel.

For the purpose of illustrating my invention, I have shown in the accompanying 20 drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

30 Referring to the drawings in which like reference characters indicate like parts.

Figure 1 represents a perspective view of a corner section of a novel screen frame structure embodying my invention.

35 Figure 2 represents a perspective view of a corner section of a modified form of a novel screen frame structure embodying my invention.

Figure 3 represents a similar perspective 40 view of a corner section illustrating a third modification of my novel metallic screen.

Figure 4 represents a horizontal sectional view of a novel screen frame embodying my invention, on the line 4—4 of Figure 1, 45 composed of vertical stiles of the construction shown in Figure 1, a top rail of the construction shown in Figure 2, and having a bottom rail of a construction shown in Figure 3, all integrally united.

50 Figure 5 represents a modified section of a rail similar to that shown in Figure 2, having a rounded outer edge.

Figure 6 represents a modified section of a rail similar to that shown in Figure 3, 55 rounded at the outer edge.

Figure 7 represents a section of a rail similar to that shown in Figure 3, illustrating a modified means of securing a screen to the frame, which is adaptable to 60 any one of the rails or stiles shown in Figures 1, 2, and 3.

Referring to Figure 1 of the drawings, 1 designates a rail or stile of my novel metallic screen which is formed by extruding a 65 suitable metal through a properly shaped

die, in a hot and plastic condition. The stile 1 shown in Figure 1, is adapted chiefly to vertically sliding screens, and consists of the inner screen retaining recess or channel 2, along the inner edge thereof, a guiding 70 channel or recess 3 along the outer edge thereof, and a plurality of central webs 4 and 5 between the guiding channel 3 and the screen retaining channel 2. The screen 6 extending over the frame 7, is secured at 75 its edges by means of the locking strip 8, which is an inverted U shape metallic channel strip, by forcing said inverted U-shaped anchoring strips into the screen retaining channel 2, as shown in each of the Figures 80 1, 2, and 3, over the edges of the screen 6, thereby locking said screen within said screen retaining channel 2.

If desired all four sides of the frame 7 may be formed of the rail 1 shown in Figure 1, by uniting mitred ends of said rails by means of welding or fusion, thus producing continuous, integral and solid metal frame structure. Instead of using the rail 1 shown in Figure 1, I may use as the top and bottom rails of my screen frame, or possibly only as the top rail, the rail 14 shown in Figure 2, of the same outside dimensions as that shown in Figure 1, having the central web 5 is moved outwardly 95 towards the outward edge, as is designated by the numeral 9 in Figure 2, thus forming a larger tubular portion 10, than that designated by 11 in Figure 1, by this means an equally rigid structure is produced, and at the same time eliminating moreover the outer guiding channel 3 when such is not desired as at the top rail.

If added rigidity is desired, as in the case 100 of the lower rail 12 of the frame, it is within the scope of my invention, to make the body portion 13 of said rail or stile solid, as shown in Figure 3, thereby imparting greater rigidity and strength to such member.

In constructing the metal screen frame according to my invention, I may avail myself of any one, several, or all of these rails shown in Figures 1, 2, and 3, to produce the said continuous and integral structure shown in Figure 4, having the bottom rail 12 and the top rail 14, and the stiles 15 and 16 in the embodiment of my invention shown in Figure 4. The bottom rail 12 is provided with the solid body 13, shown particularly in Figure 3, while the top rail has the hollow body 14 as illustrated in Figure 2, while the side stiles are provided with the outer guiding channel 3, as illustrated in Figure 1. Figure 4 shows very clearly the method of uniting the various stiles and rails into an integral structure by welding the same together along mitred end edges.

If it is desired to produce a hinged screen instead of a sliding screen 7, as illustrated

at Figure 4, I may provide for the stile members, such as shown in Figures 5 and 6, having the body portions 13 either hollow or solid as shown in Figures 5 and 6 and 5 having outer edges 19 rounded so as to produce a close fitting joint along the hinged edge in any position of the frame.

I may also provide a second modified form of a screen locking and anchoring device 20, 10 within said screen retaining channels 2, consisting of a spline 20 of substantially rectangular form or cross section, and having a groove 21 along one side thereof, which is engaged by a series of set screws 22 along 15 the length of said rails and stiles, extending through and threaded into the central webs 4 or 5, or being passed through threaded openings 23, within solid body portions 13, in which case said body portions are recessed as shown at 24 so as to receive the 20 head 25 of said set screw.

It is thus clearly seen from the above description that the screen of my novel construction embodies a number of distinct advantages; among them, the extreme strength and resistance of the frame members, against any force tending to crush the same, as well as the perfect and intimate unison of the several frame members, resulting in 25 a structure indestructible for all practical purposes, which is a decided improvement over the built-up sheet metal screen frame heretofore in use, which are subject to indentations and crushing due to external 30 forces. My construction, moreover being stronger and more rigid, will permit the use of narrower frame members, thus excluding less light and air when in position, and being of neater design and less conspicuous. 35 The general appearance of the completed screen is further enhanced by the fact that no joints are visible.

The solid metal construction possesses the further advantage that some of the metal of 40 the body portions 13 may be removed without materially impairing the rigidity of the frame. This is of particular utility when small adjustments in size of the finished frame are necessary to correct for errors in 45 measurement, as well as in cases where parts of the frame must be cut away to clear obstructions on the sill, such as shutter fasteners. Such alterations and adjustments by removing part of the metal are impossible 50 with sheet metal screen frames, since any removal of metal of any frame member will materially impair the strength of the same.

Having thus described my invention what 55 I claim as new and desire to secure by Letters Patent, is:—

1. In a metallic screen, a frame composed 60 of integral extruded metal rails and stiles, a screen retaining channel in a face of said 65 frame, a screen cloth extending over said

frame and having its edges extending into said channel and a screen cloth retaining anchor member in said channel.

2. In a metallic screen, a frame composed 70 of integral extruded metal rails and stiles, composed chiefly of aluminum, a screen retaining channel in a face of said frame, a screen cloth extending over said frame and having its edges extending into said channel, and a screen cloth retaining anchor 75 member in said channel.

3. In a metallic screen, a frame composed 80 of integrally extruded metal rails and stiles, outer guide channels in the outer edges of said frame, and inner screen retaining recesses in a face of said frame formed simultaneously with the extrusion of said rails and stiles, a screen fabric extending over said frame, and means for securing the edges 85 of said screen fabric in said recesses.

4. In a metallic screen, a frame composed 90 of integrally extruded metal rails and stiles, having outer guide channels to receive guide strips, a screen retaining recess in each of said rails and stiles, a screen cloth extending over said frame, and having its edges extending into said recess, and means to retain the edges of said screen cloth in said screen retaining recess.

5. In a metallic screen, a frame composed 95 of integrally extruded metallic rails and stiles, composed chiefly of aluminum, having outer guide channels to receive guide strips, a screen retaining recess in each of said rails and stiles, a screen cloth extending over said 100 frame, and having its edges extending into said recess, and means to retain the edges of said screen cloth in said screen retaining recess.

6. In a metallic screen, a frame composed 105 of integrally extruded metal frame members, outer guide channels in the outer edges of said frame, a screen retaining recess along the inner edges of said frame, a screen fabric extending over said frame and having its edges positioned in said recess, and a screen 110 fabric retaining anchor member seated within said recess, for securing the edges of said screen fabric therein.

7. In a metallic screen, a frame composed 115 of integrally extruded aluminum frame members, outer guide channels in the outer edges of said frame, a screen retaining recess along the inner edges of said frame, a screen fabric extending over said frame and having its edges positioned in said recess, and a screen fabric retaining anchor member seated within said recess, for securing the edges of said screen fabric therein.

8. In a metallic screen, an integral frame 120 composed of integral extruded metal frame members, an inner screen retaining channel in a face of said frame along the inner peripheral edges thereof, screen cloth extending over said frame and having its 125 130

edges extending into said channel, and a screen cloth retaining anchor member in said channel.

9. In a metallic screen, an integral frame composed of extruded aluminum alloy frame members, an inner screen retaining channel in a face of said frame along the inner peripheral edges thereof, screen cloth extending over said frame and having its edges extending into said channel, and a screen cloth retaining anchor member in said channel.

10. In a metallic screen, a frame composed of double channelled integral extruded metal rails and stiles, integrally united, one of said channels of each rail and stile being in the face of the frame and the other of said channels being in the outer edges thereof.

11. In a metallic screen, a frame composed of double channelled integral extruded aluminum alloy rails and stiles, integrally united, one end of said channels of each rail and stile being in the face of said frame and the other of said channels being in the outer edges thereof, a screen fabric extending over said frame and having its edges positioned in said face channels, and a screen fabric anchor member in said channels to lock the edges of the fabric therein.

12. In a metallic screen, a frame composed of integral extruded metal rails and stiles, outer guide channels in the edges of said frame adapted to receive guide strips, inner screen retaining channels in a face of said frame, screen fabric extending over said frame having its edges positioned in said screen retaining channels, and screen fabric retaining anchor members seated in said screen retaining channels over the edges of said fabric to lock the same therein.

13. In a metallic screen, a frame composed of integral extruded metallic rails and stiles composed chiefly of aluminum, outer guide channels in the edges of said frame adapted to receive guide strips, inner screen retaining channels, in a face of said frame, screen fabric extending over said frame having its edges positioned in said screen retaining channels, and screen fabric retaining anchor members seated in said screen retaining channels over the edges of said fabric to lock the same therein.

14. A metallic screen frame consisting of extruded metallic rails and stiles and having screen cloth retaining recesses formed in said rails and stiles during the extrusion thereof, for receiving edges of a screen fabric, and means coacting with said recesses for securing the edges of the screen fabric therein.

15. A metallic screen frame consisting of extruded metallic rails and stiles, integrally united by fusion, each of said rails and stiles having screen cloth retaining recesses formed therein during the extrusion thereof,

for receiving the edges of a screen fabric, and means coacting with said recesses for securing the edges of the screen fabric therein.

16. A metallic screen frame consisting of extruded aluminum rails and stiles and having screen cloth retaining recesses formed in said rails and stiles during the extrusion thereof, for receiving edges of a screen fabric, and means coacting with said recesses for securing the edges of the screen fabric therein.

17. A metallic screen frame consisting of extruded aluminum rails and stiles, integrally united by fusion, each of said rails and stiles having a screen cloth retaining recesses formed therein during the extrusion thereof, for receiving the edges of a screen fabric, and means coacting with said recesses for securing the edges of the screen fabric therein.

18. A metallic screen frame consisting of extruded rails and stiles, each of said rails and stiles having a screen retaining channel formed in a face thereof along the inner edges of said frame.

19. A metallic screen frame consisting of extruded metallic rails and stiles composed chiefly of aluminum integrally united by fusion, each of said rails and stiles having a screen retaining recess formed in a face of said frame and along the inner edge of said frame.

20. A metallic screen frame composed of integrally extruded metallic rails and stiles each having a substantially parallel walled screen retaining channel formed in a face thereof and screen cloth retaining anchor members adapted to seat in said channels and to coact with the parallel walls thereof to retain the edges of the screen fabric therein.

21. A metallic screen frame composed of integrally extruded metallic rails and stiles composed chiefly of aluminum, each having a substantially parallel walled screen retaining channel formed in a face thereof and screen cloth retaining anchor members adapted to seat in said channels and to coact with the parallel walls thereof to retain the edges of the screen fabric therein.

22. The method of making metallic screen frames for doors, windows, and the like which consists in extruding a rail from plastic metal, therewith forming a screen retaining recess in a face thereof, transversely severing said rail at predetermined points to form frame members and lastly rigidly uniting the terminals of said frame members end to end at angles to each other to form a rigid and continuously closed frame with the screen retaining recess in a face thereof.

23. The method of making metallic screen frames for doors, windows, and the like which consists in extruding a rail from plas-

- tic metal, therewith forming a substantially parallel walled screen retaining channel in a face thereof, transversely severing said rail at predetermined points to form frame members and lastly rigidly uniting the terminals of said frame members and lastly rigidly uniting the terminals of said frame members end to end at angles to each other to form a rigid and continuously closed frame 20 with the screen retaining recess in a face thereof.
25. The method of making metallic screen frames for doors, windows, and the like which consists in extruding a rail from plastic metallic material composed chiefly of aluminum, therewith forming a substantially parallel walled screen retaining channel in a face thereof, transversely severing said rail at predetermined points to form frame 25 members and lastly rigidly uniting the terminals of said frame members end to end at angles to each other to form a rigid and continuously closed frame with the screen retaining channel in a face thereof.
- 10 24. The method of making metallic screen frames for doors, windows, and the like which consists in extruding a rail from plastic metallic material composed chiefly of aluminum, therewith forming a screen retaining recess in a face thereof, transversely severing said rail at predetermined points to form frame members and lastly rigidly uniting the terminals of said frame mem-
- 15 bers end to end at angles to each other to form a rigid and continuously closed frame 20 with the screen retaining recess in a face thereof.

25. The method of making metallic screen frames for doors, windows, and the like which consists in extruding a rail from plastic metallic material composed chiefly of aluminum, therewith forming a substantially parallel walled screen retaining channel in a face thereof, transversely severing said rail at predetermined points to form frame 20 members and lastly rigidly uniting the terminals of said frame members end to end at angles to each other to form a rigid and continuously closed frame with the screen retaining channel in a face thereof.

ARTHUR L. OTTO.
